DAMPENING MECHANISM CONTROL MEANS
FOR ROTARY OFFSET PRINTING PRESSESEdward F. Dell, Chicago, Ill., assignor, by mesne
assignments, to Davidson Corporation, a cor-
poration of Illinois

Application April 29, 1949, Serial No. 90,509

11 Claims. (Cl. 101—148)

1

My present invention relates to improvements in printing presses and more particularly to offset printing presses embodying new and improved dampening fountain means.

In the art of offset printing, a lithographic plate is first required to be dampened and then inked after which the ink image of the plate is transferred to a blanket, which, in turn, provides for the transfer of the ink image to a sheet to be printed. These lithographic plates may vary considerably in the amount of context thereon which reflects itself in the required amount of dampening solution which need be applied to the plate to effect the satisfactory printing of sheets by the offset process.

It is an object of my invention to provide a dampening fountain of simple and economic construction embodying means whereby the application of dampening solution to a lithographic plate may be conveniently and easily regulated and adjusted to meet the requirements for the satisfactory re-production of printed sheets.

The above and other objects of my invention will appear from the following detailed description of a preferred embodiment of my invention.

Now in order to acquaint those skilled in the art with the manner of constructing and utilizing printing presses constructed in accordance with the principles of my present invention, I shall describe in connection with the accompanying drawings, a preferred embodiment of my invention.

In the drawings:

Figure 1 is a side elevational view of a printing press embodying my present invention, and in which the near side wall of the press is broken away to illustrate more clearly, in side elevation, the dampening fountain means of my invention.

Figure 2 is a view largely in front elevation but with certain parts shown in section, illustrating primarily the arrangement of the dampening fountain means of my invention with the press of Figure 1 with the view being taken substantially along the line 2—2 of Figure 1, looking in the direction indicated by the arrows;

Figure 3 is a plan view of the dampening fountain means of my invention;

Figure 4 is a side elevational view of the dampening fountain of my invention applied to the press shown in Figure 1, but showing the printing cylinder in a position for effecting engagement of the dampening or water form roll with the dampening or water fountain roll;

2

Figure 5 is a plan view of the sheet ejector means of my invention which, as previously noted, is shown in side elevation Figure 1;

Figure 6 is a detail side elevational view showing the sheet ejector means and with the printing cylinder in position at which a sheet is being stripped therefrom;

Figure 7 is a partial sectional view illustrating in side elevation a sheet gripper means having means for raising the leading edge portion of a printed sheet in the stripping of the sheet from the printing cylinder; and

Figure 8 is a plan view of a portion of the sheet gripper means of Figure 7.

15 Referring now more particularly to Figure 1 of the drawings, I have shown a printing press having an upper main frame comprising a pair of spaced side walls 7 and 8 supported on a suitable base structure 9 of which only a portion is illustrated in these drawings.

The press shown in the drawings is of a construction more fully disclosed in the copending application of William Ward Davidson, Serial No. 68,458, filed December 31, 1948. The press includes a plate and platen cylinder 10 of known construction. The cylinder 10 is mounted between the side walls 7 and 8 on a shaft 12 which extends between and is supported at its opposite ends for rotation in suitable bearings carried by the side walls.

30 The plate and platen cylinder 10 as is known, comprises a plate segment 14 and a platen segment 15, each of a circumferential extent of slightly less than half of the circumferential extent of the whole cylinder with the plate segment 14, as is known, providing for the support thereon of a lithographic plate, or the like.

35 A blanket cylinder 16 is disposed substantially immediately above the plate and platen cylinder 10 and it is carried by a shaft 17 which extends between the side walls 7 and 8 and is suitably journaled at its opposite ends therein. The blanket cylinder 16 carries a transfer blanket 18 of rubber or the like.

40 The plate and platen cylinder 10 and the blanket cylinder 16, per se are well known in the art, and it is believed that a further detailed description of these cylinders is not essential for an understanding of my present invention. The 45 constructions of these two cylinders may vary widely and the only essential requirement is that such cylinders be of a character to provide a printing couple for printing a sheet. The plate and platen cylinder 10 is of twice the diameter 50 of the blanket cylinder 16 so that for each com-

plete revolution of the plate and platen cylinder 10, the blanket cylinder is rotated twice.

The platen segment of cylinder 10, and the blanket 18 of the blanket cylinder 16 form a printing couple in a known manner. In the rotation of the plate and platen cylinder 10 in a counter-clockwise direction, as indicated by the arrow in Figure 1, the plate carried by the plate segment is adapted to be dampened by the dampening means of my present invention, shown generally at 20, and then inked by a suitable inking means indicated generally at 22. Upon rotation of the printing plate with the blanket 18 of the blanket cylinder, the ink image of the plate is transferred to the blanket 18 carried by the blanket cylinder 16. Upon feeding of a sheet between the printing couple formed by the blanket 18 of the blanket cylinder and the impression or platen surface of the platen segment 15, the ink image on the blanket is transferred to the sheet. Thus, for each full revolution of the plate and platen cylinder 10 and two full revolutions of the blanket cylinder 16, the lithographic plate carried by the plate segment is caused to be dampened and inked for transferring an ink image to the blanket 18 of the blanket cylinder 16, and the ink image transferred from the lithographic plate to the blanket 18 of the blanket cylinder 16 is transferred by the latter to a sheet fed between the printing couple formed by the blanket 18 and the platen segment 15.

It will be understood that a suitable form of drive means is provided for rotating the printing cylinder and such drive means may be embodied in the base structure 9. The drive means may include a drive gear 23 carried on a drive shaft 24 and which drive gear 23 has meshing engagement with a gear 25 carried on a shaft 26 mounted on its opposite ends in the side walls 7 and 8. The gear 26 has meshing engagement with an end gear (not shown) on the plate and platen cylinder 10 in a known manner and the plate and platen cylinder 10, in turn, is geared in a conventional way to the blanket cylinder 16 so that the drive means effects rotation of the cylinders of the press. The arrangement of the drive means is such that the plate and platen cylinder 10 and the blanket cylinder 16 are caused to be continuously rotated.

In the press in which my present invention has embodied, the plate and platen cylinder 10 carries sheet gripping means as indicated generally at 30 and shown in greater detail in Figures 7 and 8. The sheet gripping means 30 is mounted across the leading edge of the platen segment 15 and comprises a shaft 32 carrying a plurality of movable gripping fingers 33, one of which is shown in Figures 7 and 8. These gripping fingers are adapted to clamp the leading edge of a sheet to a grip bar 34 secured to the platen segment. A suitable coil spring 35 is provided for each gripping finger 33. The spring member 35, as shown, is formed with coiled end portions, with the free ends thereof being anchored in the grip bar 34 and in which the coiled ends are connected by a U-shaped portion 36 adapted to extend transversely of the grip finger closely adjacent and in engagement with the free end thereof to bias normally the grip finger to closed position with respect to the grip bar 34. The shaft 32, as shown in Figure 1, at one end thereof carries a crank arm 37 to the outer end of which a cam follower 38 is rotatably mounted. A stationary cam 39 is mounted inwardly of a side wall of the upper frame of the press in a conventional manner and

in the path of movement of the follower 38 so that as the follower 38 rides upwardly on the cam 39, each of the gripping fingers 33 are caused to be moved away from the grip bar 34 against the force of the springs 35 in proper timed sequence in the operation of the press to receive a sheet fed thereto as from a hand feed board indicated generally at 40. If desired, suitable power drive feed roll means may be provided for effecting the delivery of the sheets to the open gripper means in lieu of the hand feed board 40 as shown in the drawing. A suitable feed mechanism for such purpose is disclosed in the aforementioned co-pending application of William Ward Davidson.

Referring again to Figures 7 and 8, it will be observed that a thin sheet metal ejector finger 42 is secured to the gripper finger 33 for movement therewith. Preferably an ejector finger is provided for each gripping finger 33. The ejector finger 42 is formed with a body portion 43, substantially U-shape in cross section, which fits over the top and the sides of the gripping finger 33, and further includes arms 44, the free ends of which are adapted to be engaged with the under surface of a sheet on the platen segment in stripping of the sheet from the platen segment. A gripper opening cam 45 is suitably mounted to a side wall of the press to lie in the path of the follower 38 at the rear of the press with the cam 45 serving, upon engagement of the follower 38 therewith, to rock the shaft 32 to position the gripper finger 33 and the ejector finger 44 to the position shown in Figure 7. A stripper blade member 49 extends transversely between the side walls 7 and 8 of the press and is disposed relative to the cam 45 so that upon raising of the ejector fingers 42 to the position shown in Figure 7, the sheet is positioned with the leading edge portion thereof in position above the surface of the blade 49 to effect stripping of the sheet from the platen segment of the plate and platen cylinder 10. The cam 39, previously referred to, for opening the gripper means 30 to receive a sheet, has the cam opening surface thereof with which the follower 38 is adapted to engage arranged so that the free ends of arms 44 of the ejector fingers 42 do not project beyond the periphery of the platen segment so that in opening of the gripper means to receive a sheet, the ejector fingers do not interfere with free movement of the sheet into the open gripper means 30. In this instance, however, the gripper fingers 33 are raised sufficiently so as to receive a sheet fed thereto from the hand feed board 40.

The sheet gripping means above described, is similar in many respects to that shown in Patents Nos. 2,374,663, dated May 1, 1945, and 2,406,205, dated August 20, 1946, both issued to the assignee of the instant application. The sheet gripper means above described, however, is provided additionally with one or more ejector fingers 42, which as described, serve to effect stripping of a sheet from the printing cylinder.

The press above described embodies pressure roll means operable with the aforescribed ejector fingers 42 and stripper blade 49 and such pressure roll means is indicated generally at 50. The pressure roll means referred to forms the subject matter of my application, Serial No. 157,686, filed April 24, 1950, and which application is a division of my present application. The pressure roll means 50, in the main, provides for effecting pressure engagement of a sheet on the platen segment in effecting stripping of the sheet therefrom with the cooperative operation

of the ejector fingers and stripper blade 49 already described.

The pressure roll means 50, as best shown in Figures 5 and 6, comprises a frame member 52 which is pivotally mounted at its opposite ends by means of pivot studs 53 and 54 mounted respectively in the side walls 7 and 8 of the frame for the press. The pivot studs 53 and 54 provide for support of the frame 52 for pivotal movement about an axis extending substantially parallel with the axis of the plate and platen cylinder 10. The frame member 52, as shown, is substantially U-shape as viewed in plan, to provide for the support between the outer ends of the legs 56 thereof of a pressure roll shaft indicated generally at 57. Suitable mounting bolts 58 are carried by the leg members 56 of the main frame 52 and are provided with eccentrically disposed end stud portion 59 which project into openings provided therefor at the opposite ends of the pressure roll shaft 57. The pressure roll shaft 57 provides for the support of pressure roll means which in the particular embodiment of my invention herein disclosed, comprises two pressure rolls 60. The pressure rolls each comprise a circular disc member 62 having a hub portion 63 through which the pressure roll shaft 57 extends. A releasable leaf spring member 64 is secured at one end as by a screw 65 to each of the circular discs 62. The spring member 64 is formed with an elongated opening through which the pressure roll shaft 57 extends. Normally each leaf spring 64 has the outer or free end portion thereof normally biased in a direction for clamping a portion of the edge defining the opening therein through which the pressure roll shaft 57 extends to the latter so as to secure the pressure rolls in an adjusted position axially on the roll shaft 57. By biasing the free ends of the leaf spring members 64 toward the pressure wheels 62, the latter may be moved axially along the shaft 57 so as to engage the sheet on the periphery of the platen segment as desired in effecting the stripping of narrow or wide sheets printed by the press or for other circumstance where it may be desired to effect engagement of the pressure roll means with the sheet at a particular portion thereof.

The frame member 52 adjacent one end of the bight portion thereof has an angle flange 66 secured thereto and to which a follower carrier member 66 is pivotally connected as at 67. The follower carrier member 66 is formed with an upwardly extending lug or ear 68 between which and the opposed bight portion of the frame 52 a coil spring 69 is disposed. The follower carrier 66 provides for rotatably supporting a cam follower 70 by means of a pin 72 suitably secured in the carrier 66 and retained therein as by means of a snapping 73.

The arrangement is such that spring 69 provides for normally retaining the carrier frame 66 in fixed position with respect to the frame member 52 with the spring serving, however, to yield, permitting pivotal movement of the follower carrier member with respect of the frame member 52 under certain circumstances as will be hereinafter related.

Referring again to Figures 1 and 6, it will be observed that a coil spring 74 has connection at one end with one of the lugs of the member frame 52 and at its other end to a pin 75 carried by side wall 7. The spring 74 normally tends to bias the frame member 52 and the follower carrier 66 in a clockwise direction about the axis defined by pivot pins 53 and 54 to urge the fol-

lower 70 toward the plate and platen cylinder 10.

The plate and platen cylinder 10 is provided with a pair of form roll cams 77, one being secured at each of the ends of the platen segment of the cylinder. The cam 77 lying inwardly of the side wall 7 is disposed in alignment with the cam follower 70 so that as the plate and platen cylinder rotates, engagement of the cam follower 10 with the form roll cam 77 last referred to effects slight counterclockwise movement of the frame member 52 of the pressure roll means 50 about the axis defined by the pivot studs 53 and 54 to engage the pressure rolls 62 with the sheet 15 on the platen segment in effecting the stripping of the sheet in the manner already above described.

The structure above noted compensates for varying thicknesses of sheets printed by the press 20 in the following manner. The form roll cam 77 and the cam follower 70 may, for example, be adjusted to provide the desired pressure engagement of the pressure roll means 62 with a sheet of a given thickness on the platen segment. For example, this sheet may be of a minimum thickness normally used for printing purposes, say of .002 inch with the adjustment being made to provide for the proper pressure contact of the pressure roll means 62 with a sheet of that thickness. 25 With the press thus adjusted and upon printing sheets of greater thickness, the increased thickness of the sheet is compensated for by compression of the coil spring 69 between the frame member 52 and the follower frame carrier 66 upon engagement of the follower 70 with the form roll cam 77 so that the pressure roll means 62 effect substantially uniform pressure engagement with the sheet on the platen segment in the stripping of such thicker sheets from the platen segment.

40 Referring now to Figures 1 through 4, it will be observed that the dampening fountain means 20 of my present invention comprises a tray 80 arranged to extend transversely between the main side walls 7 and 8 and is supported by a pair of links 82 at each of the ends thereof with the links 82 at their lower ends having pivotal connection as at 83 with the tray 80 and at their upper ends having pivotal connection as at 84 to brackets 85 which are secured one adjacent each the inner surfaces of the side walls 7 and 8. The links 82 thus provide for limited swinging movement of the tray 80 virtually in a substantially horizontal plane between the side walls 7 and 8 of the press.

The links 82 at opposite ends of the tray 80 toward the front of the press have nut members 81 pivotally secured thereto as by rivets 79. Bolts 87 having threaded connection with nuts 85 are provided with knob members 88 at their outer ends and these knob members are normally held against depending flanges 89 of the brackets 85 by coil springs 90 encircling the bolts 87 and disposed between the inner surfaces of the flanges 89 and nuts 92 threaded on the bolts 87. The coil springs 90 urge the link members 82 having the pivotally mounted nut members 81 thereon in a direction for moving the dampening tray 80 inwardly of the press with the extent of such inward movement being limited by engagement of the knobs 88 with the flanges 89 of the brackets 85.

The dampening fountain means 20 further comprises a conventional dampening or water fountain roll 100 carried by a shaft 102 which is suitably journaled at its outer end in the end walls of the tray 80. As best shown in Figures 2 and 3, the end walls 105 of the tray are formed with

integral lugs 106 to which leaf spring members 107 are secured at one end as by screws 108. The opposite ends of the leaf springs 107 carry brake members 110 in position for engaging the fountain roll shaft 102 at the portions thereof between the opposite ends of the fountain roll 100 and the inner journal portions of the tray 80 for the opposite ends of the shaft 102. The leaf spring members 107 bias the brake members 110 into an engagement with the shaft 102 to restrain free rotation of the water fountain roll 100.

The dampening fountain means 20 further comprises a dampening or water form roll 115 provided with a fabric covering for retaining the dampening solution. The water form roll 115 is carried by a shaft 117, the opposite ends of which are journaled in a pair of mounting members 118 disposed inwardly of side walls 7 and 8 of the press and pivotally mounted thereon as indicated at 119. The mounting members 118 are each formed with a yoke shaped portion 120 for receiving the ends of the shaft 117 and substantially C-shaped retaining members 122 are provided for retaining the opposite ends of the shaft 117 within the yoke-shaped portions 118. Coil springs 123 have connection with the C-shaped retaining members 122 and at their other ends to pins 125 secured to the side walls of the press to retain the water form roll in position in the mounting members 118.

The members 118 each, further, are formed with an offset flange member 130 carrying a set screw 132 which is adapted to engage a shaft 134 extending transversely of the press between the side walls 7 and 8 thereof so as to limit the extent to which the coil springs 123 are adapted to dispose the water form roll 115 inwardly toward the plate and platen cylinder 10. The shaft 134 is provided with a flat 135 which the inner ends of the set screws 132 engage to define the operative position of the water form roll 115. The shaft 134 is rotatable and upon engagement of the circular peripheral surface portion thereof with the ends of the set screws 132, the water form roll 115 is moved to an inoperative position.

As best illustrated in Figure 2, the shaft 117 is provided with a pair of water form roll cam followers 140 in alignment with the form roll cams 77 at the opposite ends of the platen segment 15 so that in movement of the platen segment 15 past the water form roll 115, the latter is disposed to a position out of engagement with the surface of the platen segment. Immediately inwardly of the water form roll cam followers 140, fountain cam followers 142 are provided and these followers are in alignment with a dampening fountain cam 145 secured as by the screws 146 in juxtaposition inwardly of and intermediate the ends of form roll cams 77. Thus, in the rotation of the plate and platen cylinder 10 the dampening fountain cams 145 are adapted to engage the water fountain cam followers 142 to effect movement of the water form roll 115 in a direction to engage it with the water fountain roll 100 mounted in the dampening tray 80. The dampening fountain cams 145, as best shown in Figure 4, are provided with a raised central portion 150 which, when engaged with the water fountain cam followers 142, effect the aforescribed operation. Upon engagement of the water form roll 115 with the fountain roll 100 the tray 80 is moved outwardly of the press against the force of the coil springs 90, and after the dampening fountain cam 145 has travelled beyond the water fountain cam followers 142

the springs 90 are effective for returning the tray to its initial position.

By virtue of the above described construction, the tray 80 of the dampening fountain means 5 may be disposed in a selected position relative to the form roll 115 so as to provide for a selective period of engagement of the water form roll 115 with the fountain roll 100. If, in a printing operation being carried out with the press, only a limited amount of dampening solution is desired for the lithographic plate carried by the plate segment, the tray 80 may be positioned so that when the water form roll 115 is caused by the dampening fountain cams 145 to move toward the fountain roll 100, only slight limited peripheral engagement is provided therebetween so that the water form roll 115 picks up only a limited amount of dampening solution from the fountain roll 100. Conversely, if substantial dampening solution is required, the tray 80 may be positioned further inwardly of the press so that it is retained in peripheral engagement with the form roll 115 for a greater length of time, thus providing for the transfer of a larger amount of dampening solution to the water form roll 115 and in turn to the plate carried by the plate segment.

By virtue of the aforescribed construction, the dampening fountain 20 may be positioned 30 relative to the water form roll 115 so as to provide for the desired amount of peripheral engagement of the water form roll 115 with the water fountain roll 100.

The ink fountain means, indicated generally at 35 22, comprises a main or ink distributor roll 150 carried by a shaft 152 which is journaled at its opposite ends in suitable bearings carried by the side walls 7 and 8. A pair of brackets 153 are disposed adjacent the inside surfaces of the side walls 7 and 8 and are formed with yoke portion 154 at the upper ends thereof which support the ends of a shaft 156 which carries an ink form roll 158. The shaft 156 is retained in position in the yoke ends 154 of the brackets 153 by a substantially C-shaped retaining member 160. A coil spring 162 is connected to one end of each of the clamp members 160 and is anchored at its other end as 163 to a side wall of the press. The springs 162 normally draw the retaining clamps 160 inwardly to retain the shaft 156 in the yoke ends of the brackets 153. The brackets 153 are further formed with offset flanges 160 in which adjustable set screws 162 are mounted, and which set screws are adapted to engage the shaft 163' extending between the side walls 7 and 8. The set screws, by engagement with the shaft 163', define reaction points for the springs 162 for effecting pressure engagement of the ink form roll with the printing plate on the plate segment of the plate and platen cylinder 10. The shaft 163' is provided with a flat which the inner ends of the set screws engage in the operative position of the inking means 22, and upon rotation of the shaft 115 to engage the cylindrical surface thereof with the ends of the set screws. The ink form roll is disposed to its inoperative position when that is desired in the operation of the press. The supply roll 159 of the inking means 22 is provided with a gear indicated generally at 170, which meshes with a drive pinion 172. The drive pinion 175 in turn is adapted to be driven by the aforementioned gear at the end of the plate and platen cylinder. In the form of the ink means shown in the drawings, the ink distributor roll does not operate in a fountain

but rather ink is applied thereto manually as by means of a collapsible tube or other applicator in the desired amount for effecting inking of the lithographic plate carried by the plate segment. The form roll 150 further embodies ink form roll cams 175 which are adapted to engage the form roll cams 174 at the ends of the platen so as to raise the ink form rolls off of the platen segment as it passes the inking apparatus 22. As shown, the ink form roll is also provided with an end drive gear 178 which is adapted to have meshing engagement with the gear 170 of the fountain roll 150 so as to effect rotation of the ink form roll in the application of ink to the plate on the plate segment.

While I have shown and described what I consider to be certain preferred embodiment of my invention, it will be understood that various modifications and rearrangements may be made therein without departing from the spirit and scope of my invention.

I claim:

1. Dampening means for an offset printing press of a character having a rotatable printing cylinder and in which the cylinder carries form roll cam means comprising, form roll means biased toward said cylinder and adapted to be engaged by said form roll cam means to be disposed in a position out of an engagement with said cylinder, dampening fountain means including fountain roll means, mounting means for mounting said dampening fountain means for movement toward and away from said form roll means comprising, stop means for limiting movement of said dampening fountain towards said form roll means, spring means for urging said dampening fountain means against said stop means, and second cam means adapted to be carried by said cylinder for moving said form roll means to a position in engagement with said fountain roll means.

2. Dampening means for an offset printing press of a character having a rotatable printing cylinder and in which the cylinder carries form roll cam means comprising, form roll means biased toward said cylinder and adapted to be engaged by said form roll cam means to be disposed in a position out of an engagement with said cylinder, dampening fountain means including fountain roll means, mounting means for mounting said dampening fountain means for movement toward and away from said form roll means comprising, stop means for limiting movement of said dampening fountain means toward said form roll means, spring means for urging said dampening fountain means against said stop means, second cam means adapted to be carried by said cylinder for moving said form roll means to a position in engagement with said fountain roll means, and means for said stop means for adjusting the position of said dampening fountain means with respect to said form roll means.

3. Dampening means for an offset printing press of a character having a printing cylinder mounted in a main frame and including plate and platen segments, and in which the platen segment carries form roll cam means comprising, form roll means, spring means for biasing said form roll means in a direction to engage the same with said cylinder, follower means for said form roll means engageable with said form roll cam means for moving said form roll means away from said platen segment against said spring means, a dampening fountain, mounting means including bracket means adapted to be secured to

said main frame of said press and link means between said bracket means and said fountain for supporting the latter for swinging movement toward and away from said form roll means, stop means between said bracket means and said link means for limiting movement of said dampening fountain toward said form roll means, spring means yieldingly resisting movement of said dampening fountain in a direction away from said form roll means, a fountain roll rotatably mounted in said fountain, and second cam means adapted to be carried by said platen segment and engageable with said follower means for engaging said form roll means with said fountain roll and moving said dampening fountain away from said stop means against the force of said spring means, whereby said form roll means is adapted to have engagement with said fountain roll.

4. The dampening fountain means of claim 3 characterized by the provision of an adjustment screw for the stop means for adjusting the position of the dampening fountain relative to the form roll means to provide for adjustment of the extent of peripheral contact of the form roll means with the fountain roll.

5. Dampening means for an offset printing press of a character having a printing cylinder mounted in a main frame and including plate and platen segments, and in which the platen segment carries form roll cam means comprising, form roll means, spring means for biasing said form roll means in a direction to engage the same with said cylinder, follower means for said form roll means engageable with said form roll cam means for moving said form roll means away from said platen segment against said spring means, a dampening fountain, mounting means including bracket means adapted to be secured to said main frame of said press and link means between said bracket means and said fountain for supporting the latter for swinging movement toward and away from said form roll means, stop means between said bracket means and said link means for limiting movement of said dampening fountain toward said form roll means, spring means yieldingly resisting movement of said dampening fountain in a direction away from said form roll means, a fountain roll rotatably mounted in said fountain, and second cam means adapted to be carried by said platen segment and engageable with said follower means for engaging said form roll means with said fountain roll and moving said dampening fountain away from said stop means against the force of said spring means, whereby said form roll means is adapted to have engagement with said fountain roll, and brake means carried by said dampening fountain and engageable with the fountain roll for restraining rotation of the latter.

6. Dampening means for an offset printing press of a character having a printing cylinder mounted in a main frame and including plate and platen segments, and in which the platen segment carries form roll cam means comprising, form roll means, spring means for biasing said form roll means in a direction to engage the same with said cylinder, follower means for said form roll means engageable with said form roll cam means for moving said form roll means away from said platen segment against said spring means, a dampening fountain, mounting means including bracket means adapted to be secured to said main frame of said press and link means between said bracket means and said fountain for supporting the latter for swinging movement toward and away from said form roll means, stop

means between said bracket means and said link means for limiting movement of said dampening fountain toward said form roll means, spring means yieldingly resisting movement of said dampening fountain in a direction away from said form roll means, a fountain roll rotatably mounted in said fountain, and second cam means adapted to be carried by said platen segment and engageable with said follower means for engaging said form roll means with said fountain roll and moving said dampening fountain away from said stop means against the force of said spring means, whereby said form roll means is adapted to have engagement with said fountain roll, said stop means including adjustment screw means for adjusting the position of the dampening fountain relative to the form roll means to provide for adjustment of the extent of peripheral contact of the form roll means with the fountain roll, and brake means carried by said dampening fountain and engageable with the fountain roll for restraining rotation of the latter.

7. In a fountain means for an offset printing press having a rotatable printing cylinder and form roll cam means carried at a portion thereof, the combination of form roll means including a pair of cam follower means biased toward said cylinder, one of said cam follower means being adapted to be engaged by said form roll cam means to dispose said form roll means out of engagement with said cylinder, a fountain including rotatable fountain roll means, and means carried by said cylinder in juxtaposition of a portion of said form roll cam means for engaging the second of said cam follower means of said form roll means to move the latter into engagement with said fountain roll means.

8. In a fountain means for an offset printing press having a rotatable printing cylinder and form roll cam means carried at a portion thereof, the combination of form roll means including a pair of cam follower means biased toward said cylinder, one of said cam follower means being adapted to be engaged by said form roll cam means to dispose said form roll means out of engagement with said cylinder, a fountain including rotatable fountain roll means, and means carried by said cylinder in juxtaposition of a portion of said form roll cam means for engaging the second of said cam follower means of said form roll means to move the latter into engagement with said fountain roll means, and means for adjusting the position of said fountain toward and away from said form roll means.

9. In a fountain means for an offset printing press having a rotatable printing cylinder and form roll cam means carried at a portion thereof, the combination of form roll means including a pair of cam follower means biased toward said cylinder, one of said cam follower means being adapted to be engaged by said form roll cam means to dispose said form roll means out of engagement with said cylinder, a fountain including rotatable fountain means, means carried by

said cylinder in juxtaposition of a portion of said form roll cam means for engaging the second of said cam follower means of said form roll means to move the latter into engagement with said fountain roll means, and brake means for said fountain roll means for restraining the latter against rotation.

10. In a fountain means for an offset printing press having a rotatable printing cylinder and form roll cam means carried at a portion thereof, the combination of form roll means including a pair of cam follower means biased toward said cylinder, one of said cam follower means being adapted to be engaged by said form roll cam means to dispose said form roll means out of engagement with said cylinder, a fountain including rotatable fountain roll means, means carried by said cylinder in juxtaposition of a portion of said form roll cam means for engaging the second of said cam follower means of said form roll means to move the latter into engagement with said fountain roll means, means for adjusting the position of said fountain toward and away from said form roll means, and brake means for said fountain roll means for restraining the latter against rotation.

11. Dampening means for an offset printing press of a character having a rotatable printing cylinder and in which the latter is provided with form roll cam means comprising, dampening fountain means including fountain roll means disposed adjacent said cylinder, said form roll means between said dampening fountain means and said cylinder, said form roll means having a pair of cam followers, means for said form roll means for biasing the same toward said cylinder and away from said dampening fountain, one of said cam follower means of said form roll means being adapted to be engaged by said form roll cam means for moving said form roll means away from said cylinder, and second cam means carried by said cylinder in juxtaposition of a portion of said form roll cam means for engaging the second of said cam follower means for moving said form roll means to a position to engage the same with said fountain roll means.

EDWARD F. DELL.
